UNITED STATES PATENT OFFICE.

MOSES G. FARMER, OF NEWPORT, RHODE ISLAND.

ELECTRIC LIGHTING SYSTEM.

SPECIFICATION forming part of Letters Patent No. 252,836, dated January 24, 1882.

Application filed June 7, 1881. (No model.)

To all whom it may concern:

Be it known that I, MOSES G. FARMER, a citizen of the United States, residing at the United States naval torpedo station in the city and county of Newport, and State of Rhode Island, have invented certain new and useful Improvements in Electric Lighting Systems, as well as new and improved apparatus thereto pertaining, of which improvements the following is a specification.

My invention relates more particularly to the organization of the so-called "incandescent" system of electric lighting, or that in which a current of electricity is caused to traverse one or more sections of a conductor, which sections are composed of some suitable conducting material refractory to heat, having a considerably higher resistance per unit of length than the remainder of the circuit, and by means of such resistance a portion of the electricity which traverses the circuit is converted into heat, which, when of sufficient intensity, produces light. These ends I attain by arranging the lamps of an electric-light system in branch or derived circuits, connected with the main line of conductors, and inserting in one of said branch circuits a device or apparatus regulated by the variations of the strength of current in the branch circuit, which correspondingly controls a device or apparatus for regulating the strength of current traversing the main circuit. The subject-matter claimed is herein-after specifically designated.

In the accompanying drawings, Figure 1 is a plan view of the apparatus. Fig. 2 is a theoretical diagram, illustrating the electric circuits and the relation of the different parts of the mechanism to each other; and Fig. 3 is a diagram graphically representing the law of development of light by electric action.

In Figs. 1 and 2 of the drawings I have shown three electric lamps, L^1 , L^2 , and L^3 , which are respectively placed in three separate branches of one electric circuit. It will be understood that the lamps need not necessarily be placed in the same position with reference to the regulator that they occupy in Fig. 1, but that they may be placed wherever their light is required, while the regulating mechanism may also be placed at any convenient point.

I will first describe the construction and mode

of operation of one of these lamps, and will afterwards explain the mechanism which I have devised for automatically maintaining a uniform strength in the electric current traversing them.

If a bar, wire, or strip of platinum, iridium, or other similar refractory substance, which is also a conductor of electricity, be rendered incandescent by the passage through it of an electric current of sufficient power, a mild and pleasant light is emitted thereby, which is much less concentrated and glaring than that obtained in the ordinary way from an arc formed between carbon pencils, and is also of more uniform brilliancy, provided the electric current be constantly maintained at a uniform strength. Platinum—one of the most refractory metals—affords a light equivalent to about one hundred candles per square inch of incandescent surface when within 220° of its temperature of fusion, while iridium, owing to its higher melting-point, produces a still greater amount of light under the same conditions. In accordance with this principle I prefer to construct my electric lamp of a bar or strip of one of the hereinbefore-mentioned metals by affixing the same in an upright position between two metallic standards, P^3 and P^4 , by means of suitable clamps, P' and P'' , as shown in Fig. 2, the electric current being made to pass through the said strip.

The quantity of light which is emitted by an incandescent body at a high temperature is proportionally much greater than that at a lower temperature. When, therefore, heat is developed by the passage of an electric current through a resisting-conductor, its temperature increases in a much more rapid ratio than the increase in the strength of the current. The ratio of the development or emission of light from a platinum conductor, for example, is represented graphically in Fig. 3 of the drawings. If the increase in the strength of the current from zero to a strength sufficient to fuse the platinum conductor be observed at equidistant intervals, and the intensity or amount of light emitted at the several points of observation be measured, the ratio of the increase of light will be represented with substantial accuracy by the curved line in the figure. It will be obvious from this diagram that the relative cost of producing a given

light will decrease rapidly as the absolute strength of current is augmented. Thus it requires only about twice the absolute strength of current to fuse a strip of platinum that it does to render it faintly luminous, and the amount of light emitted just below the temperature of fusion is about five times that which would be obtained with a current of seven-eighths of the strength. While, therefore, a high temperature must be maintained in the incandescent lamp for the sake of economy, it is obvious that a slight variation in the strength of the current at such a temperature will make a very great difference in the amount of light emitted. The object of my regulating apparatus therefore is to so regulate the strength of current as to secure economy, as well as uniformity, in the light.

I will next explain the mechanism whereby a uniform current of any desired degree of strength is maintained in each lamp or series of lamps.

One of the main conductors proceeding from the electric generator, which may be a dynamo-electric machine, a galvanic battery, or any other suitable source of electricity, is attached to the binding-screw C^4 , and the current proceeding from the generator passes from thence to the binding-screw C^5 , through an automatically-adjusted rheostat, to be hereinafter described, thence by the conductor v to the binding-screw C^2 , and thence by the conductor v' , dividing at $j^1 j^2 j^3$ into three branches or derived circuits leading respectively to the three lamps $L^1 L^2 L^3$. These branches again unite upon a single main conductor, v^2 , at the respective points $j^4 j^5 j^6$, which main conductor is united at the binding-screw C' with the return conductor leading back to the other pole of the electric generator.

The automatic regulator which is interposed in the main conductor leading from the source of electricity, and which is consequently in that portion of the circuit which is common to all the branches and lamps in the system, may be constructed in various ways, the general principle being that any increase in the strength of the current shall simultaneously set in action mechanism causing a gradually-increasing resistance to be interposed in the circuit, while the opposite effect will take place when the strength of the current is diminished. One very effective arrangement which I have devised for this purpose is illustrated theoretically in Fig. 2, and is also shown and described in detail in another division of this application, herein referred to. The principle of this apparatus will be sufficiently well understood by reference to the diagram Fig. 2 in connection with the following description:

G' is a cylinder or roller, constructed of non-conducting material and mounted upon a metallic support, D^6 . G^2 is another cylinder or roller, of metal, of similar size and form, mounted upon a metallic support, D^7 . A flexible conductor, R , of some metal offering consider-

able specific resistance to the passage of an electric current, has one of its ends connected with the axle and metallic support D^8 of the non-conducting roller G' , and is wound several times around the periphery of the said roller, (the convolutions being of course insulated from each other,) and thence passes across to the metallic roller G^2 and a number of times around its periphery in the opposite direction. It being premised that one end of the flexible conductor R is electrically connected with the binding-screw C^4 and the other with the binding-screw C^5 , it will be readily understood that the rotation of both rollers G' and G^2 in such a direction as to wind the conductor from one to the other, as indicated by the arrow, would have the effect of increasing the resistance of the circuit between the points C^4 and C^5 , because the current is obliged to pass through such portion of the whole length of the conductor R as is not in contact with the metallic roller G^2 . Therefore the greater the portion of its length that is wound upon the insulating-roller G' and off from the metallic roller G^2 the greater will be the resistance in circuit, and, conversely, the less it will become when the conductor is wound in the opposite direction. The required movement of the rollers G' and G^2 in one direction or the other is preferably effected by means of an independent motor, M^5 , the particular construction and arrangement of which are immaterial. Any known form of electro motor (of which the one shown in diagram in Fig. 2 is a type) will serve the purpose well. The electric current for actuating such a motor may be derived from an independent source of electricity; or it may be taken from the main current, which supplies the lamps, by means of a branch or derived circuit, the former plan being usually preferable. The pinion P^2 receives its motion from said motor, and is capable of being shifted in one direction or the other, so as to engage with one or the other of the toothed wheels, $F^1 F^2$, which are mounted upon the respective axles of the rollers G' and G^2 . As the electro-motor M^5 , when in action, always revolves in the same direction, carrying with it the pinion P^2 , it is obvious that the rollers G' and G^2 will be caused to rotate in one direction or the other, according as the pinion P^2 is engaged with one or the other of the toothed wheels $F^1 F^2$.

I will now explain the mechanism whereby the pinion P^2 is shifted and the manner in which this shifting is automatically effected by the increase or decrease of the strength of the current in the main conductor.

Referring to Figs. 1 and 2, M' represents a pair of electro-magnetic or magnetizing helices, which are placed in one of the branch circuits uniting the poles of the generator.

m represents a pair of movable soft-iron cores, which tend to be drawn into helices when rendered magnetic by the action of the electric current, the distance which they are thus drawn depending upon the strength of the current.

The movable cores *m* are attached to one end of a horizontal beam or lever, *B*, pivoted at or near its center upon a standard, *F*, the attractive force of the helices being opposed by the constant force of an adjustable antagonistic spring, *2*. The lever *B* is capable of a slight vertical oscillation upon its axis, which is limited in each direction by adjustable screw-stops *f* and *b*. One pole of a battery or other generator of electricity, *X*, is connected with the standard *F* by means of wire *w'*, which terminates in a binding post, *C*². The adjustable contact-screw *f* is connected by the wire *w*² with binding-post *C*⁷, and thence by wire *w*⁴ with an electro-magnet, *M*³. Similarly the contact-screw *b* is connected by the wire *w*³, binding-post *C*⁶, and wire *w*⁵ with the electro-magnet *M*⁴. The electro-magnets *M*³ and *M*⁴ are connected by wires *w*⁷ and *w*⁶, respectively, with a common binding-post, *C*⁸, to which the remaining pole of the generator is connected. This circuit may, if preferred, be supplied with electricity from the main circuit, which supplies the lamps, instead of making use of a separate generator.

It will be understood, from the explanation which has been given, that as the lever *B* is deflected from its normal position of equilibrium under the greater or less attraction exerted by the regulating-helices *M'* in opposition to the constant force of the spring *2*, an electric current will be directed through one or the other of the electro-magnets, *M*³ *M*⁴, as the case may be.

By reference to Fig. 2 it will readily be understood that the electro-magnet *M*³, when in action, will by the force of its attraction throw the pinion *P*² into gear with the wheel *F'*, and in like manner the electro-magnet *M*⁴ will throw the pinion into gear with the wheel *F*². Thus, if the current in the main conductor, and consequently that in the several branch conductors, tends to become too strong, the core *m'* of the regulating-magnet *M'* will be attracted, causing the lever *B* to make contact with the point *f*, thus throwing the electro-magnet *M*³ into action, which shifts the pinion *P*² in such a manner as to cause the motor *M*⁴ to interpose a gradually-increasing resistance in the circuit, in the manner hereinbefore explained, and thus reduce the strength of the current traversing the regulating-helices *M'*, as well as the several branch circuits and lamps, until the attraction in the magnet *M'* becomes sufficiently diminished, when the antagonistic spring *2* will come into action and interrupt the contact at *f*, thus preventing further increase of the resistance. A decrease in the normal strength of the current will produce the reverse effect upon the balanced lever *B*, and will also reverse the above-described mechanical operation, bringing the electro-magnet *M*⁴ into action, and thus withdrawing the necessary amount of resistance from the main circuit. By this means the current traversing the entire system of main and branch circuits, which includes the lamp or lamps, will be au-

tomatically maintained at a practically-uniform strength, and this normal strength may be made greater or less at pleasure by varying the tension of the spring *2* or the position of the contact-stops *f* and *b*.

A regulator, in order that it may adequately control the operations of an extended system of lights, must not only be capable of maintaining a constant normal strength of current in each of a definite number of branches, but it must also, without the necessity of readjustment, be capable of restoring said normal strength when by reason of the addition to the circuit of one or more branches the said strength tends to diminish, or when by reason of the withdrawal of one or more branches said strength tends to increase. The successful accomplishment of this end is a feature of the system herein described, in which, as has already been shown, the rheostat is placed in the main or common circuit, and is controlled by a governor operated by a branch current. This cannot be effected by any system in which the governing apparatus is located in the main circuit, for in that case the addition of an extra branch would diminish the joint resistance of the branches, thereby increasing the strength of current in the main circuit, while diminishing the strength in each branch, thus causing the governor to interpose additional resistance in the main circuit, which would still further lessen the branch currents, instead of restoring them to their normal strength. On the other hand, let the governor be operated by a branch current, the addition of an extra branch tends to diminish the current throughout the entire circuit, including that which traverses the branch in which the governor is located. The latter, by withdrawing resistance from the main circuit, operates to increase the current throughout the entire circuit until the normal strength in the governor-branch is restored; but this is simultaneous with the restoration of the normal strength in each of the lamp-branches. In other words, the governor continually calls for the normal strength of current in its branch, and whatever be the number of branches, such normal strength is therein secured only upon the restoration of the normal strength in each of the remaining branches.

This application constitutes a division of one filed by me January 19, 1880, serial No. 965, which exhibits a convenient organization of apparatus for carrying out the objects of my invention.

I do not herein claim gradually varying the resistance of an electric-light circuit, nor the details of the regulating apparatus by which the same is effected, as these constitute the subjects-matter of other pending divisions of the above-mentioned application. I do not, however, herein limit myself to the specific construction and organization of apparatus shown, as the details of such apparatus may be greatly varied without departing from the principle of my invention.

It is advisable to include one or more electric lamps in the branch which contains the governing apparatus of the regulator, said lamps having conductors of similar electrical properties to those in the remaining branches. The object of this is that a change may be effected in the specific resistance of the governing branch similar to those occurring in the lamp-branches under the influence of a change in temperature.

I claim as of my own invention—

1. In an incandescent electric lighting system, the method hereinbefore described of uninterruptedly controlling the strength of current of a main line of continuous conductors by and correlative with incidental variations of strength in the same current traversing a continuous branch circuit.

2. In an incandescent electric lighting system, the method hereinbefore described of varying the strength of current of a main line of continuous conductors by dynamic effects produced by variations of strength in the same current traversing a continuous branch circuit.

3. In an incandescent electric lighting system, the method hereinbefore described of automatically controlling the strength of current traversing a main line of continuous conductors by and correlative with incidental variations of strength in the same current traversing continuous branch circuits in which the lights are included.

4. The combination, substantially as set forth, of a generator of electricity, separate branches or derived circuits uniting the poles or main conductors thereof, mechanism for varying the strength of the current flowing through said conductors, means for controlling the current-varying mechanism included in one of the branches and actuated by the current flowing therein, and an electric lamp or lamps included in each of the other branches.

5. The combination, substantially as hereinbefore set forth, of a generator of electricity, two or more separate branches or derived circuits connecting the poles or main conductors of said generator, mechanism for regulating the strength of the electric current in the main and branch circuits included in one of said branch circuits and actuated by variations in the current traversing the same, and one or more electric lamps included in the remaining branch or branches.

6. The combination, substantially as hereinbefore set forth, of a generator of electricity, two or more separate branches or derived circuits connecting the poles or main conductors of said generator, mechanism for regulating the strength of the electric current in the main and branch circuits, an electro-magnetic helix included in one of said branch circuits for controlling said regulator, and one or more electric lamps included in the remaining branch or branches.

7. The combination, substantially as hereinbefore set forth, of a generator of electricity, two or more separate branches or derived circuits connecting the poles or main conductors of said generator, one or more electric lamps included in each of said branches, an adjustable rheostat included in that portion of the circuit of the generator common to all the lamps, and mechanism, substantially such as described, whereby the resistance of said rheostat is diminished as the joint resistance of the whole number of lamps is increased, and the reverse.

In testimony whereof I have hereunto set my hand this 4th day of June, 1881.

MOSES G. FARMER.
